UNITED STATES PATENT OFFICE

97,398

DESIGN FOR A TOILET PAPER HOLDER

Walker M. Levett, New York, N. Y.

Application August 27, 1935, Serial No. 58,320

Term of patent 3½ years

To all whom it may concern:

Be it known that Walker M. Levett, a citizen of the United States and resident of New York, in the county of New York and State of New York, has invented a new, original, and ornamental Design for a Toilet Paper Holder, of which the following is a specification, reference being had to the accompanying drawing, forming part thereof, in which the figure is a perspective view of a toilet paper holder showing my new design.

I claim:

The ornamental design for a toilet paper holder, as shown.

WALKER M. LEVETT.
